SUPPORTING STRUCTURE

William J. Masoner, Chicago, Ill.

Application November 7, 1934, Serial No. 751,820

4 Claims. (Cl. 248—323)

This invention relates to a new and improved supporting structure and more particularly to a structure for supporting apparatus hung from a ceiling or from cross joists of a building.

5 It has been found desirable in many instances to support heavy structures from the ceilings of buildings, such structures for example, as heating and ventilating apparatus. Such apparatus may comprise unit heaters, radiators, blowers or the like. While my improved supporting structure will support apparatus of this character it will be understood that the invention is independent of the particular form of apparatus which it is to support.

10 15 A number of methods have been used heretofore to support apparatus of this character in rooms or areas to be heated. In general such methods include the use of comparatively heavy supporting timber which are bolted to ceiling beams or secured to the beams by hooks which are hooked over the ceiling beams. These structures generally are unsightly and do not admit of adjustment of the location of the supported apparatus. In many cases after the apparatus, such

20 25 as a unit heater, has been suspended from the ceiling it will be found that the angle at which it is placed does not properly distribute or direct the heat. With usual types of suspensions it is necessary to take down the supporting structure 30 to change the position of the heater. This causes additional injury to the ceiling in finished rooms and also requires additional labor expense.

It is an object of the present invention to provide a new and improved supporting structure 35 for suspending apparatus from ceiling beams or the like.

It is an additional object to provide a structure 40 in standard form which is adapted for use with different spacings and sizes of supporting beams and with different sizes of apparatus to be supported.

It is also an object to provide a device which may be quickly installed and which results in a minimum of injury to a ceiling.

45 45 It is a further object to provide a device which is capable of adjustment of the supported structure without movement of the structure secured to the ceiling beams or the like.

50 It is an additional object to provide a structure with an associated canopy which covers the supporting structure and may be readily changed in position with the supporting structure.

It is also an object to provide suitable temporary supporting means for use in supporting

apparatus while it is being secured to the permanent supporting structure.

It is a further object to provide a device which is simple in design, composed of but few parts, and adapted for commercial production and installation.

Other and further objects will appear as the description proceeds.

I have shown a preferred embodiment of my invention in the accompanying drawings in which—

Figure 1 is an elevation showing my improved device supporting a heater or the like;

Figure 2 is a horizontal section taken on line 2—2 of Figure 1;

Figure 3 is a cross section taken on line 3—3 of Figure 2.

Figure 4 is a section on an enlarged scale, taken on line 4—4 of Figure 2;

Figure 5 is a section on an enlarged scale, taken on line 5—5 of Figure 2; and

Figure 6 is a section on an enlarged scale, taken on line 6—6 of Figure 2.

In the drawings, the joists 11 support a ceiling construction 12, which may consist of lath and plaster, metal wall board or other material. The hanger hooks 13 have hooked ends extending over the tops of the joists and have threaded lower ends on which are placed the nuts 14, supporting heavy washers 15. The washers 15 support the spaced U bars 16 which are spaced by the tubular members 17 which fit on the tie bolts 18. This assembly of U bars, spacing members and tie bolts comprises the upper or fixed frame which is supported and positively secured to the ceiling by the hanger hooks 13.

The tie plate 19 extends across between the lower legs of the U bars 16 and supports the bolt 20, which in turn supports the lower tie plate 21. This lower tie plate 21 fits under the upper legs of the U bars 22, which, with the spacers 23 and tie bolts 24, form the lower or movable frame.

The lower legs of the U bars 22 support the floor flanges 25 into which are threaded the upper ends of the pipe hangers 26. As shown in Figure 1, the lower ends of the pipe hangers 26 are connected by couplings 27 to the upper ends of the support pipes 28 of the unit heater 29.

The canopy 30 is designed to cover both the upper and lower frames regardless of their relative angular position. The canopy is supported by and moves with the lower or movable frame. As shown in Figure 2, the canopy is an elongated octagon but it may obviously be made in other

shapes if desired. It must have a width greater than the upper or fixed frame and a length greater than the lower or movable frame. It is formed with sides 31 which engage the ceiling 12. The 5 angle members 32 are secured to the inner face of the canopy 30, as shown in Figures 1 and 2, by spot welding or in any other desired manner. The strap 33 passes over the lower frame and is secured to the angles 32 by the bolts 34. Openings 35 are formed in the sides 31 of the canopy 30 so that the bolts 34 may be adjusted to tighten the strap 33 and bring the edges of the sides 31 of the canopy tightly against the ceiling 12.

As shown in Figure 2, the canopy 30 may have 15 two sets of spaced openings 36 and 37. As shown in the drawings, the pipe hangers 26 pass through the outer set of openings 37. The swinging cover plates 38 are formed in pairs and are so disposed as to cover the unused openings. These plates 38 20 are pivoted on screws or bolts 39 and may be readily removed and reversed in position if the other pair of openings 36 is to be used. It will be apparent that the floor flanges 25 may be slid back and forth as desired, and thus the supporting structure and canopy shown may be used for 25 two standard spacings of pipe hangers 26 in connection with two standard sizes of space heaters or the like. The lock nuts 40 engage the undersides of the cover plates 38 and assist in supporting 30 the canopy 30.

It is believed that the method of assembling and using the supporting device will be apparent from the drawings and the description. The hanger hooks 13 are used where it is practical to 35 have the hooks pass over the upper side of the supporting beams, but it will be understood that other usual types of securing means may be substituted. Where the beams carry a floor upon their upper sides, the hooks may pass through 40 the beams, or screws or other standard securing and supporting members may be substituted for hooks. It will be apparent that these supporting means may be spaced at any desired distance apart within the limits of the length of the upper 45 supporting frame. Consequently, the device may be supported from beams of any spacing within that limit. Obviously also the upper and lower supporting frames may be made of any size to correspond to any beam spacing and any necessary spacing of supporting members.

The upper supporting frame is preferably placed at right angles to the line of direction of the beams and in order to secure it in place it is only necessary to make holes through the plaster 55 or other ceiling material sufficiently large to insert the hooks 13 of the equivalent supporting members. The securing means are then tightened up to bring the upper supporting frame against the ceiling or against the lower face of 60 the beams if no ceiling is present. This may be done with the lower frame attached to the upper frame, or the lower frame may be removed for convenience while attaching the fixed frame. The lower frame may be swung to any desired 65 angle with the upper frame and clamped firmly in place by tightening up the bolt 20.

If a canopy is to be used, the canopy is slipped upwardly over the pipe hangers 26 and the lock

nuts 37 screwed up to hold the canopy in place. The strap 33 is placed over the lower supporting frame and may be tightened up by the screws 32 so as to bring the edges of the canopy firmly against the ceiling. In case it is desired to change the angular adjustment of the lower frame relative to the upper frame, the canopy may be readily dropped down so that the bolt 20 may be loosened. It may be possible also to swing the lower frame without loosening this bolt, as sufficient leverage is afforded by the widely spaced pipe hangers 26 so that the frictional grip of the washers 19 and 21 may be overcome without loosening the bolt 20.

The various parts may be made in different sizes to suit different weights and shapes of apparatus to be supported and I contemplate such changes and modifications as come within the spirit and scope of the appended claims.

I claim:

1. Supporting apparatus comprising elongated upper and lower frame members, each frame comprising spaced inwardly facing U-shaped members held in place by spacing connecting members, means adjustably connecting the two members, connecting means having portions slidable between the U-shaped members of the upper frame and having upwardly extending portions for connecting the upper frame to a supporting structure, and means for connecting a device to be supported to the lower frame.

2. Supporting apparatus comprising elongated upper and lower frame members, each frame comprising spaced inwardly facing U-shaped members held in place by spacing connecting members, means adjustably connecting the two members, connecting means having portions slidable between the U-shaped members of the upper frame and having upwardly extending portions for connecting the upper frame to a supporting structure, and supporting means having portions slidable between the U-shaped members of the lower frame and having downwardly extending portions for supporting a device below the lower frame.

3. In combination with supporting apparatus comprising relatively movable upper and lower frames, means adjustably connecting the two members, means for securing the upper frame to ceiling beams or the like, a canopy for covering said frames, means connected to the canopy and passing over the lower frame for securing the canopy to the lower frame and urging the edges of the canopy toward the ceiling beams or the like.

4. In combination with supporting apparatus, comprising relatively movable upper and lower frames, means adjustably connecting said frames, a canopy for covering said frames, means for securing the canopy to the lower frame, supporting members extending downwardly from the lower frame, a plurality of spaced openings in the canopy, certain of said openings serving to permit passage of the supporting means, and adjustable means for closing the openings not used by the supporting means.

WILLIAM J. MASONER.
